Application November 5, 1956, Serial No. 620,553

2 Claims. (Cl. 235—185)

This invention relates to a multiplying device which employs means for establishing electrically a predetermined vectorial relationship between analog voltages representing the quantities to be multiplied and the analog voltage representing their product.

Computers are known in the art for multiplying analogs which employ a potentiometer driven by another potentiometer or a servo mechanism. The accuracy of the output of these devices is limited by their sensitivity and degree of calibration. This invention contemplates the provision of a pair of adding networks and a variable voltage divider connected between the networks. The output of the second network is similarly connected to the voltage divider through a phase sensitive device and represents the product of two analog voltages respectively placed into the adding networks when the system has been stabilized. The analog inputs in the adding networks are 90° out of phase and when the output of the second network is placed in phase with the analog input for the first network by means of the phase sensitive device and the variable voltage divider the system is stabilized. The operation of the system may be established by well known geometric principles using vectors to represent voltage amplitude and phase. Preferably the second network is adapted to receive a predetermined fraction of the analog voltage of the first network and its reference voltage in order to improve the versatility and accuracy of the system.

One object of the invention therefore, is to provide a multiplying device the mode of operation of which is exclusively dependent on electrical means.

Another object of the device is to provide an electrical multiplier having improved accuracy and versatility.

Other objects and advantages of the invention may be appreciated on reading the following detailed description in conjunction with the accompanying drawings, in which:

Fig. 1 is a schematic illustration of the arrangement of units which constitute the computing system;

Fig. 2 is a vector diagram showing the voltage relationships established by the first adding network;

Fig. 3 is a vector diagram showing the voltage relationships established by the second adding network after correction by a demodulator; and

Fig. 4 is a vector diagram showing the voltage relationships established by the second adding network before correction by the demodulator.

According to Fig. 1 a potentiometer 1 is referenced by reference voltage A of approximately 8 volts and zero degrees phase on line 2 and is driven by means of shaft 3 which is settable in accordance with an input quantity X. A three legged adding network 4 is connected to the potentiometer 1 by a lead 5 which serves to introduce analog voltage output E_x into the network. A second leg of the network 4 is connected to lead 6 on which there is placed a reference voltage B of approximately 8 volts and ninety degrees phase. A single channel amplifier 7 is connected to the adding network 4 by lead 8 and the

amplifier output on line 10 is placed on the third leg of the adding network 4 by means of feedback line 11.

The lead 10 is connected to one side of variable voltage divider 12 which comprises a resistor 13 and is series connected to one side of a non-linear resistance bridge 14 the other side of which is grounded.

A line 15 connects one leg of a second adding network 16 to the voltage divider 12 at a point between the resistor 13 and the resistance bridge 14 and carries a voltage E_o .
 10 A second leg of the adding network 16 is connected to the output side of potentiometer 17 by means of lead 18. The potentiometer 17 is referenced by the ninety degree phase voltage E_b on lead 20 and is driven by shaft 21 settable in accordance with a second input Y. The output 15 of the adding network 16 on lead 22 is amplified by a second amplifier 23 whose output voltage E_p on lead 24 represents the product of the two quantities X and Y. The output is fed back to a third leg of the adding network 16 on feedback line 25 and when the latter is nulled 20 the complete output of the network box on lead 24 is assured. There is provided an output lead 26 connected to lead 24 for feeding the analog product E_p to an appropriate indicator (not shown).

As shown below it is necessary to insure that the voltage E_p on the lead 24 is in phase with the analog voltage E_x in the adding network 4. The voltage E_x is assumed to have a phase of zero degrees. It is therefore required to detect the presence of voltages having a ninety degree phase relation thereto and adjust the input of adding network 16 to remove the same from its output. Accordingly, a phase sensitive demodulator 27 which is set to pass voltages of ninety degrees phase and remove voltages of zero degrees phase every half cycle is connected to lead 24 through a switch 28, an attenuator 29, which reduces 30 the voltage input to the demodulator, and lead 30. Preferably a filter and integrator network 31 is provided to receive the demodulator output of the demodulator 27 on lead 32 serving to stabilize the system by reducing the fluctuations of the voltage divider output E_o .

40 The output of the filter and integrator 31 is fed to a modulator 33 on lead 34 to convert the signal to A. C. for the following amplifier comprising a transformer 35 and servo amplifier 36 which are connected to the modulator 33 by means of lead 37. The amplifier signal is 45 then placed in rectifier 37 by lead 38 and a D. C. filter 40 by lead 41 whereupon the signal is fed to the resistance bridge, 14. The resistance bridge 14 comprises four equal resistances R_1 , R_2 , R_3 and R_4 . Lead 42 and lead 43 connect the filter across the bridge in one direction 50 while its opposite points are connected to resistor 13 and ground. Any change in the filter supply voltage causes a corresponding change in the IR drops across the individual bridge resistors and hence across the bridge itself. The voltage drop across the bridge is thereby controlled by the demodulated signal to attenuate the voltage E_o , which is the adjusted voltage output, V of the adding network 4, so as to eliminate Y voltage components from the output of the adding network 16.

55 In order to improve the range and versatility of the 60 multiplier and to enable it to operate with negative analogs of the Y input a fourth leg of the adding network 16 is connected to the lead 5 by means of lead 44 having a resistor 45 provided therein whereby the voltage $E_x/2$ may be introduced to the network. The reference voltage $E_b/2$ is placed on a fifth leg of the adding network 16 by means of connection 47.

65 As mentioned above the operation of the device depends on means for phase controlling the input and output voltages of the adding networks. The amplified 70 output of the adding network 4 is the voltage V which is the resultant of the reference voltage E_b and the analog

voltage E_x . The first vertical triangle is thereby established as shown in Fig. 3. The voltage V is then applied as voltage E_o to the input circuit of the adding network 16 by means of the variable voltage divider 12. The input to the amplifier 23 comprises at least three voltages, E_o , E_y and output voltage E_p , and desirably reference voltage $E_b/2$ and analog voltage $E_x/2$. The resultant voltage E_p is generated by the amplifier and fed back to the adding network 16. This establishes the second triangle shown in Fig. 2. It can be seen that a voltage E_p could exist at the output of the amplifier 23 even if the demodulator circuit did not exist. However, without the demodulator circuit the second triangle would not necessarily be similar to the first established triangle and could be a triangle as shown in Fig. 4. The function of the demodulator circuit and voltage divider is, therefore, to attenuate the voltage E_o so that the phase of voltage E_p is rotated clockwise until it is positioned ninety degrees from E_y . When the voltage E_p is ninety degrees out of phase with E_y , the second triangle has become similar to the first and E_p is proportional to the product of the input quantities X and Y . In order for the voltage divider to attenuate the voltage V so that the voltage E_p has no Y component voltage, the demodulator must sense Y components of E_y in the output voltage E_p . To accomplish this the demodulator contacts are operated in phase with E_y ; thus, the demodulator is sensitive to voltage in phase with E_y while components of voltage having the desired phase of E_p will cancel during each half cycle of operation, and only components of the amplifier output in phase with E_y will pass to the output of the demodulator. This detected voltage will be integrated and amplified in the demodulator circuit to vary the attenuation of the voltage V until the only voltage at the output of amplifier 23 is E_p [0°].

The voltage divider, therefore, must have the characteristic that the equivalent resistance of the bridge will change proportionately with the demodulated signal.

It is understood that the invention is independent of the specific units described in its preferred form, and alterations may be made therein without departing from the principle and scope of the invention as defined in the appended claims.

What is claimed is:

1. An electric multiplier comprising an adding network, means for introducing a reference and an analog voltage to said adding network, voltage attenuating means connected to the output of said adding network, a second adding network connected to the output of said voltage attenuating means, means for introducing into said second adding network a second analog voltage having a ninety degree phase difference from the analog voltage placed in the first adding network, a phase sensitive de-

modulator and amplifier connected to the output of said second adding network and in control of said voltage attenuating means, said demodulator being set to pass voltages in phase with the analog voltage placed in said second adding network, there being means for setting into said second adding network a preselected fraction of the reference and analog voltages placed into the first adding network whereby the multiplier is adapted to yield the product of the analog voltage placed in the first adding network and positive or negative analog voltage placed in the second adding network.

2. An electric multiplier comprising an adding network, means for introducing a reference and an analog voltage to said adding network, voltage attenuating means connected to the output of said adding network, a second adding network connected to the output of said voltage attenuating means, means for introducing into said second adding network a second analog voltage having a ninety degree phase difference from the analog voltage placed in the first adding network, a control circuit connected to the output of said second adding network and in control of said attenuating means, said control circuit including in series an attenuator, a phase sensitive demodulator, a modulator for converting the rectified output of said demodulator to an alternating current voltage, a transformer and amplifier for amplifying said alternating current voltage and a rectifier for reconverting said alternating current voltage to direct current voltage, said demodulator being set to pass voltages in phase with the analog voltage placed in said second adding network, there being means for setting into said second adding network a preselected fraction of the reference and analog voltages placed into the first adding network whereby the multiplier is adapted to yield the product of the analog voltage placed in the first adding network and positive or negative analog voltage placed in the second adding network.
